SAW HORSE AND TABLE COMBINATION
Albert Janda, R.R. 4, Box 13, South Elgin, Ill.
Filed May 29, 1961, Ser. No. 113,553
4 Claims. (Cl. 182—28)

The present invention relates to improvements in a combination saw buck and table support structure and is more particularly related to the novel construction of a frame assembly that is readily arranged for use as a carpenters' saw buck or as a rigid support structure for a table top.

More generally the device of the present invention is characterized by the provision of a plurality of leg elements connected to a common ridge member, pivotally or otherwise, and each provided with normally collapsed means some of which are movable into a position of use when the structure is set up for use as a saw buck and others of which are movable into a position of use when the structure is set up for use as a table support structure. When not in use, the assembly disclosed in one embodiment can be folded into substantially compact form for handling and storage.

It is therefore an object of the invention to provide a novel combination saw buck and table top support structure of the character referred to.

Another object is to provide an assembly of the character described with novelly mounted leg extensions.

Another object is to provide a saw buck assembly with telescoped leg extensions movable into positions for use as an elevated supporting structure for a table top.

Another object is to provide a combination saw buck-table support structure with novelly constructed leg elements movable from an angular position relative to a ridge bar into the plane of said bar to afford a support structure for a table top.

Still another object is to provide leg extensions on an assembly of the character described with normally concealed auxiliary leg members.

Another object is to provide a rigid structure of the character referred to which is inexpensive to construct, easy to set up for a plurality of uses and to collapse for storage, and which is very practical and efficient.

Other and more detailed advantages and objects of the invention will appear more fully as the description proceeds reference being made to the accompanying drawings wherein preferred forms of the invention are shown. It should be understood however that the drawings and description are illustrative only and should not be taken as limiting the invention except insofar as it is limited by the claims.

In the drawings:

FIG. 1 is an end elevational view of the improved structure set up for use as a saw buck.

FIG. 2 is a top plan view of the FIG. 1 disclosure.

FIG. 3 is an enlarged fragmentary longitudinal sectional view of one of the leg elements showing the leg extensions and auxiliary leg members fully contained therein; showing parts in elevation.

FIG. 4 is a transverse detail sectional view of the leg element, taken substantially on line 4—4 of FIG. 3, but showing the auxiliary leg member in elevation and extended.

FIG. 5 is a detail sectional view taken substantially on line 5—5 of FIG. 1.

FIG. 6 is an end elevational view of the novel structure set up for use as a table top support.

FIG. 7 is a view similar to FIG. 1, showing a modified embodiment of the invention.

FIG. 8 is a top plan view of the saw-buck shown in FIG. 7.

2

FIG. 9 is an end elevational view of the FIG. 7 embodiment, showing the structure set up to support a table top.

Referring to the accompanying drawings, and particularly to the embodiment shown in FIGS. 1—6, the improved structure includes an elongated channel-shape ridge bar 11, comprised of a bottom wall 12 and upstanding side walls 13. Two pairs of laterally extending spaced apart ears 14 are formed integral with each side wall 13 and with the related pairs offset one from the other longitudinally for a purpose to be explained presently. Each pair of ears 14 is adapted to receive between them, the upper end of a leg element 15 each of which also is channel shaped and has its side walls journalled, as by trunnions 16, in the respective pairs of ears so as to be pivotally movable from a support position illustrated in FIG. 1, into substantially the horizontal position illustrated in FIG. 6. When in the FIG. 1 position, the leg elements 15 constitute diverging support legs for the saw buck. Since it is frequently desirable to provide an X-formation on the top side of a saw buck to cradle a beam or other article, each leg element 15 has normally fully telescoped thereinto an extendable member 17. Preferably the free edges of the side walls of leg elements 15 have inturned flanges 18 to prevent displacement of the extendable member 17 therein.

Referring now particularly to FIG. 3, the extendable member 17 may comprise a substantially solid beam cut at an angle at its upper edge 19 so as to conform to and lie in the plane of the angular top end edge of leg element 15 when in fully telescoped position. The extendable member 17 may be withdrawn upwardly into substantially the position shown in FIG. 1 to form with the related member 17 the X-formation above referred to. Such relative positioning of members 17 is made possible by the longitudinal offsetting of leg elements 15 by reason of the aforesaid offsetting of the pairs of ears 14 at each end of ridge bar 11.

The extendable members 17 are held in extended position preferably by means of a ring pin 21 or the like, inserted through a hole 22 in the leg elements and for positioning same beneath the extended member 17. Spreading of the diverging leg elements 15 is prevented by any suitable latch means, preferably in the form of hooks 23, one removably pivoted at one end to one leg element, as at 24, and engaged over a stud 25 on the companion leg element.

When the structure is to be used as a support for a table top 26, as shown in FIG. 6, the extendable members 17 are fully telescoped into the respective leg elements 15 and said leg elements are swung about their pivots 16 into the horizontal plane of ridge bar 11. Movement into such position is limited by the presence on each leg element of at least one lug 27 preferably formed integral with the upper end of the element and offset outwardly so as to abut a related ear 14, as shown.

The leg elements are retained in such horizontal positions by auxiliary legs 28. As best shown in FIGS. 3 to 6, inclusive, each extendable member 17 has a longitudinally extending slot 29 in its bottom side that terminates at the lower end of the member 17 in a transverse circular hole 31. A bearing element 32 is journalled for free rotation in said hole and it has secured thereto one end of the auxiliary leg 28. These two parts preferably are joined as by providing a tapped opening in the bearing element to receive the threaded end 28a of said leg, although they may be otherwise secured together firmly.

The auxiliary leg normally lies within longitudinal slot 29, as illustrated in FIGS. 3 and 5, and preferably is held

in such position by frictional engagement with the side walls of said slot which is slightly narrower than the diameter of the auxiliary leg. To facilitate withdrawal of the auxiliary leg from slot 29, said slot is of a length greater than the length of the auxiliary leg so as to provide clearance for finger engagement with the end of leg 28. When withdrawn from slots 29, the legs 28 are swung into abutment with the inclined end 33 of the respective slot so as to be retained in vertical outwardly inclined positions, substantially as shown in FIG. 6. The assembly is completed by placing table top 26 over the support structure as shown.

Referring now to the embodiment disclosed in FIGS. 7 to 9, wherein like numerals are used to identify corresponding parts, the structure includes a channel shaped ridge-bar 11 to which is firmly secured, as by welding, a plurality of longitudinally offset legs 15a which may be reinforced by tie straps 34 welded or otherwise secured to the related pairs of legs. Each leg is channel shaped in section and is adapted to have telescoped endwise therein an extendable member 17a. These members may be moved into an extended position as best shown in FIG. 7 and held firmly in place by pins 35 that extend through registering openings in said extensions and legs and further secured in the cross-position illustrated by a pin 36 threaded through aligned holes in the extensions at the point of their intersection. The resulting assembly is a saw buck.

In order to use the FIG. 7-9 assembly as a table top support, or as a support for various mechanical devices such as a vise, power tool or the like, the extendable members are either telescoped into the related legs or they may be secured in the horizontal positions shown in FIG. 9.

To adapt the assembly as a support for accessory tools, one or more slide blocks 37 may be arranged in the ridge bar 11 and secured in a longitudinally adjusted position by lock screws 38 (FIG. 8). Each block may have a T-slot 39 therein to receive mounting bolts for securing the accessory tool thereto.

When the extendable members 17a are positioned horizontally as shown in FIG. 9, the pin 36 is removed and said members are swung outwardly. Each member 17a includes auxiliary legs 28 that are then swung downwardly to support the free outer ends of said members. When the extendable members are in such horizontal positions, 45 T-slot 41 in one surface thereof may be used to mount accessory tools thereon.

From the foregoing description it is believed that the nature of the invention and the manner in which it is to be carried out will be readily apparent to those skilled in this art.

5 What I claim and desire to secure by Letters Patent of the United States is:

1. A saw buck structure comprising a ridge bar, a plurality of supporting legs connected firmly at their upper ends to said ridge bar, said legs being arranged in pairs with one pair adjacent to each end of said ridge bar and one of each pair on each side of said ridge bar, the legs of each pair being offset longitudinally from one another and diverging outwardly downwardly from one another; an extendable member telescoped endwise in each leg and pivotally secured thereto, said members being movable into cross relationship extending above said ridge bar and into a plane responding to the plane of said ridge bar.

10 2. The saw buck structure recited in claim 1, in which means is provided to connect the extensions in each pair of legs at their intersection one with the other.

15 3. The saw buck structure recited in claim 1, in which auxiliary legs are carried by the extensions to support them in the plane of the ridge bar.

20 4. A saw buck structure comprising a ridge bar, a plurality of supporting legs connected firmly at their upper ends to said ridge bar, said legs being channel-shaped in section and being arranged in pairs with one pair adjacent to each end of the ridge bar and one of each pair on each side of said ridge bar, the legs of each pair being offset longitudinally from one another, an extendable member nested into each leg, and means pivotally connecting each extendable member at its upper end with the upper end of the respective leg, said members each being movable about said pivots from a position nested within a leg into a plane parallel with the plane of the ridge bar and into cross relationship extending above said ridge bar.
